US00D875749S

(12) **United States Design Patent** (10) **Patent No.:** **US D875,749 S**
Lim et al. (45) **Date of Patent:** **** Feb. 18, 2020**

(54) **DISPLAY SCREEN OR PORTION THEREOF WITH GRAPHICAL USER INTERFACE**

(71) Applicant: **Samsung Electronics Co., Ltd.,**
 Suwon-si (KR)

(72) Inventors: **Taekyeung Lim, Seoul (KR); Joonho Ok, Seoul (KR)**

(73) Assignee: **SAMSUNG ELECTRONICS CO., LTD.,**
 Gyeonggi-Do (KR)

(**) Term: **15 Years**

(21) Appl. No.: **29/583,838**

(22) Filed: **Nov. 9, 2016**

(30) **Foreign Application Priority Data**

Nov. 2, 2016 (KR) 30-2016-0052607

(51) **LOC (12) Cl.** **14-04**

(52) **U.S. Cl.**

USPC **D14/486**

(57) **CLAIM**

The ornamental design for a display screen or portion thereof with graphical user interface, as shown and described.

DESCRIPTION

FIG. 1 is a front view of a display screen or portion thereof with graphical user interface, showing our new design in a first embodiment; and,

FIG. 2 is a front view of a display screen or portions thereof with graphical user interface, showing our new design in a second embodiment.

The broken lines illustrating the display screen or portion thereof and portions of the graphical user interface form no part of the claimed design.

1 Claim, 2 Drawing Sheets
